UNITED STATES PATENT OFFICE.

JAMES M. BALDWIN, OF NEW YORK, N. Y.

FABRIC FOR FURNITURE AND WALL COVERINGS.

SPECIFICATION forming part of Letters Patent No. 288,294, dated November 13, 1883.

Application filed September 3, 1883. (No model.)

To all whom it may concern:

Be it known that I, JAMES M. BALDWIN, a citizen of the United States, residing at New York, in the county and State of New York, have invented a certain new and useful Improvement in Fabrics for Furniture-Coverings, Wall-Hangings, and for other Purposes, of which the following is a specification.

The object of my invention is to provide a fabric having an embossed leather-face surface, to be used as coverings for furniture, hangings or coverings for walls, and for other purposes, as a substitute for the ordinarily-employed solid leather; and my improvement consists in the combination, with a thin sheet of split leather, of a sheet of elastic or flexible material, whereby a body is made to support and protect the leather; also, in combining therewith a strengthening-sheet of some textile material, all as will be more fully hereinafter set forth.

Heretofore, in the employment of leather as a covering for walls or for upholstery purposes, it has been necessary to use such leathers as have a considerable thickness, in order to obtain the requisite strength and durability in the material; hence leathers fitted for this class of ornamentation, especially as wall-hangings, are very expensive, and, besides this, the application of real or solid leather to walls involves considerable labor, it being necessary to apply it in sections or panels to produce a good result.

The purpose of my invention is to produce a fabric having the appearance and finish of a solid leather, richly embossed, which can be furnished in rolls and applied to the wall in a manner similar to ordinary wall-papers, and at a small cost.

In the accompanying drawings, serving to illustrate my invention, Figure 1 is a plan or face view of my improved fabric, partly in section. Fig. 2 is a cross-section of the same; and Fig. 3 is a similar view, but without the under sheet or backing.

In making up my fabric I am enabled to use both the inner or outer grain or splits of the leather for the face or outer layer.

Let *a* in the drawings represent a thin sheet of leather—one of the inner splits—obtained by splitting or cutting ordinary leather into layers by any one of the well-known methods. To the under side of this leather is se-

cured, by cement or other adhesive substance, a sheet, *b*, of felt paper, having a sufficient body or thickness to furnish an elastic bed or support for the leather.

Where the outer grain or split of the leather is used, which has a natural body or face, the application of the felt paper or other elastic material to the leather will be sufficient; but where an inner grain is used, it is necessary to cement to the felt sheet *b* a sheet, *c*, of cotton cloth or other textile material, in order to give the combined fabric the requisite firmness to prevent any tendency of the leather to warp.

The fabric thus made is finally subjected, by suitable machinery, to produce in relief the figures *d* on the leather surface, which are brought out boldly and prominently by reason of the thickness and elasticity of the body of the fabric.

Instead of the felt paper, any other coarse flexible paper or material may be used to form the body of the fabric.

When leather is applied directly to walls, it is materially affected by any dampness, so that in moist weather it will sag or fall in ridges and become unsightly. By interposing an absorbent body between the wall and the leather, (as would be the case where my fabric is employed,) the leather may be preserved in a dry and smooth condition during damp weather.

What I claim as new, and desire to secure by Letters Patent, is—

1. As a new article of manufacture, a fabric composed of a sheet of leather and a sheet of felt or equivalent elastic material united together, as and for the purpose set forth.

2. As a new article of manufacture, a fabric constructed of a sheet of thin split leather, a sheet of cotton cloth or its equivalent, and an intermediate sheet of felt paper, cemented together, substantially as and for the purpose set forth.

3. The fabric herein described, consisting of a sheet of thin leather, a sheet of textile material, and a sheet of felt paper, united together and embossed, as and for the purposes set forth.

JAMES M. BALDWIN.
